ELECTRO-MECHANICAL MEANS FOR
REVERSING DIRECT CURRENT

John A. Pollak, Detroit, Mich., assignor to Allied Research Products, Incorporated, Baltimore, Md., a corporation of Maryland

Filed Jan. 21, 1963, Ser. No. 252,959
17 Claims. (Cl. 200—93)

This invention relates to a current reversing unit and more particularly to an electro-mechanical device for periodically reversing a D.C. current.

In many electro-chemical processes, for example, in electrolytic cleaning and in copper plating, it is desirable and sometimes necessary to reverse the current so that during one interval of time the workpiece being treated within a tank is anodic and during a successive interval of time the workpiece is cathodic. To accomplish this periodic reversal in polarity, relays have been conventionally used in the past. The use of relays for periodically reversing the polarity of D.C. current in the electro-chemical field has certain disadvantages. When it is considered that it is not unusual to employ currents as high as 3,000 amperes, the use of commercial relays, usually designed to operate at a maximum current of 50 amperes, is obviously undesirable because of the numerous relays that have to be employed. Furthermore, relays burn out frequently and this further adds to the disadvantages of using relay type current reversing devices.

It is an object of the present invention to provide an electro-mechanical device for periodically reversing the current to a pair of terminals connected to a source of direct current.

A further object of the invention resides in the provision of a current reversing unit which is of economical construction and which is adapted to carry very high currents without presenting any problem of overload.

In the drawings:

FIG. 1 is a side elevational view, partly in section, of the current reversing unit of my invention.

FIG. 2 is an end view, partly broken away and partly in section, of the current reversing unit of this invention.

FIG. 3 is a top plan view of the unit.

FIG. 4 is a sectional view along the line 4—4 in FIG. 1.

FIG. 5 is a block diagram showing in a general way the manner in which the current reversing unit of this invention is operated.

The current reversing unit of the present invention includes a housing 10 that can be economically constructed of angle iron to form generally rectangularly shaped top and bottom frames 12 and 14, respectively, which are interconnected at their ends by upright angles 16 and 18 and at the center portion of each side thereof by intermediate upright angles 20. At each side of housing 10, there is mounted, as by screws 22, a pair of plate-like supports 24 each formed with a semi-cylindrical opening 26. Supports 24 are formed of an electrical insulating material such as Bakelite. A pair of high purity copper cylindrical tubes 28 extend crosswise of structure 12 and are mounted on supports 24 by screws 30. The tubes 28 are seated at each end in the downwardly facing semi-circular seats 26 in supports 24.

At each end, housing 10 is provided with an end panel 32 which is formed of an electrical insulating material such as Bakelite. The input and output terminals extend through these end panels. The two input terminals are designated 34 and 36, respectively, and the two output terminals are designated 38 and 40, respectively. Each input terminal comprises a pair of bus bars secured together face to face and supported on their respective end panels 32 by angle brackets 42 (FIGS. 1 and 4). To the inner end of each input bus bar 34, 36, there is bolted as

2

at 44 a right angle connecting bar 46 which is likewise formed of two pieces of copper secured together in face-to-face relation. The lower horizontal leg of connecting bar 46 has bolted thereto as at 48 a tube clamp 50. Each tube clamp 50, as is shown in FIG. 1, has an arcuate portion which overlies the outer top surface of its respective tube 28 and is secured thereto in intimate electrical conducting relation by screws 52. The output terminals 38, 40 are supported adjacent their outer ends on the end panels 32 by mounting angles 54. The inner ends of terminals 38 and 40 are supported on an insulating cross bracket 56 by angles 58. Cross bracket 56 is supported at each end on the intermediate upright angles 20. Adjacent the intermediate upright angles 20, there is mounted on bottom frame 14 a pair of cross bars 60 formed of an insulating material such as Bakelite. On the top side of each cross bar 60, there are mounted as by screws 62 two Bakelite supports 64, one adjacent each side of housing 10 as shown in FIGS. 3 and 4. Each support 64 has pivotally connected thereto a contact shoe. These shoes are formed as copper castings and are designated 66, 68, 70 and 72. The pivotal connection between each support 64 and its contact shoe includes a hardened steel pin 74 on the contact shoe which is journaled in a hardened steel bushing 76 in the support 64. Each contact shoe is fashioned with a relatively wide arcuate contact face 78 which is lapped to the exact contour of the surface portion of the tube 28 with which it is adapted to engage. The contact face 78 of each shoe is cast integrally with a pair of ribs 80, the free ends of which are pivotally connected as at 82 with the lower end of a link 84.

Directly above each contact shoe, there is supported on top frame 12 an operating solenoid for the shoe. The solenoids are designated 86, 88, 90, 92. Solenoids are secured to cross angles 94 on top frame 12 by screws 96. The movable plunger 98 of each solenoid has a pair of support brackets 100 pivotally suspended therefrom. An insulating block 102 is mounted as by screws 104 on the inturned ends 106 of support brackets 100. A screw 108 extends downwardly through a hole in insulating block 102 and is threaded as at 110 into the upper end of link 84. Between the top side of insulating block 102 and the head of screw 108, there is arranged a coil spring 112. When a solenoid is energized, its plunger 98 is pulled upwardly, thus raising link 84 and pivoting the respective shoe into contact with the tube 28. Springs 112 form a yieldable connection between each solenoid and its contact shoe to accommodate for wear and assure perfect contact between the contact surface 78 of each shoe and the adjacent surface portion of the tube 28 with which it is associated.

Each contact shoe is fashioned with a terminal lug portion 114 to which an electric cable is adapted to be connected. Four such cables are provided. These are designated 116, 118, 120 and 122. Cable 116 extends from output bus bar 38 as at 124 to shoe 80. Cable 118 extends from bus bar 38 to shoe 70. Cable 120 extends from output bus bar 40 as at 125 to shoe 68 and cable 122 extends from bus bar 40 to shoe 72. These cables are flexible and are connected to their respective shoes by screws 128.

As is illustrated in the block diagram of FIG. 5, in operation, the input terminals 34, 36 of the current reversing unit of this invention are connected to the output side of a rectifier 130 which is in turn connected to a source of alternating current as indicated at 132. The output terminals 38, 40 of the current reversing unit are connected to a plating tank in a conventional manner. For the purpose of energizing solenoids 86, 88, 90, 92, a timer 134 is employed. Timer 134 may be of any conventional type, its purpose being merely to energize and

de-energize the solenoids alternately and periodically in pairs. Timer 134 is set to energize solenoids 88 and 90 simultaneously for a certain desired interval of time and then de-energize solenoids 88, 90 and energize solenoids 86 and 92 for another desired interval of time. Timer 134 is preferably arranged to cut off the current to the input bus bars 34, 36 prior to energizing and de-energizing the solenoids so as to eliminate arcing between the contact shoes and the tubes 28. Timers for alternately energizing and de-energizing solenoids in this manner are commercially available and further description of timer 134 is therefore unnecessary.

The alternate closing of the two sets of contact shoes by energizing and de-energizing their operating solenoids reverses the polarity at the output bus bars 38, 40. For example, when solenoids 88 and 90 are energized and assuming that bus bar 34 is positive and bus bar 36 is negative, then the positive current flows from bus bar 34 through its clamp 50 to tube 28 through the contact shoe 68 and cable 120 to the output bus bar 40 which is thus positive. The negative current flows from input bus bar 36 through its clamp 50 to the other tube 28 and then through contact shoe 70 and cable 118 to the output bus bar 38 which is thus negative. When timer 134 de-energizes solenoids 88, 90 and energizes solenoids 86, 92, contact shoes 68, 70 break with tube 28 and contact shoes 66, 72 are pulled up into contact with their respective tubes 28. Thus, the positive current from bus bar 34 now flows through the tube 28 through shoe 66 and through cable 116 to bus bar 38 which thus becomes positive and the negative current from bus bar 36 flows through the other tube 28 through contact shoe 72 and cable 122 to bus bar 40 which thus becomes negative.

I have thus provided an electro-mechanical device for periodically reversing the polarity of a D.C. current which is of economical construction, reliable in operation and adapted to carry very high currents without the danger of overload. The contact shoes provide a large area of contact with the tubes 28. When it is considered that about one square inch of copper contact area can safely carry about 1,000 amperes, it will be realized that each contact shoe can carry 3,000 or more amperes without any difficulty. The current carrying capacity of the contact shoes can be further increased by forced air cooling of the shoes and the copper tubes 28. This is one advantage of forming the conductors 28 as tubes. They not only provide a maximum current area for a given space but radiate heat rapidly and are easily adapted for forced air cooling so as to eliminate the problem of overheating. Furthermore, by lapping the curved contact surface 78 of each shoe to the exact contour of the portion of the copper tube which it contacts, a nearly perfect and total contact area is obtained. In addition, the use of the yielding connection between each solenoid and its contact shoe through the provision of spring 112 accommodates for wear in the contact shoes and tubes and also eliminates the need for accurate adjustment of the closed length of the solenoid links 84.

I claim:

1. A device for periodically reversing the polarity of a D.C. current comprising a pair of input terminals adapted to be connected to a source of D.C. current, a pair of output terminals, a pair of cylindrical conductors, one of said pair of terminals being electrically connected to said cylindrical conductors, a plurality of four contact shoes, one pair of said contact shoes being arranged when actuated to circumferentially engage and make contact with the cylindrical surface of one of said cylindrical conductors and the other pair of contact shoes being arranged when actuated to circumferentially engage and make contact with the cylindrical surface of the other cylindrical conductor, one contact shoe in each pair being connected to one of the terminals in the other pair of terminals and the other contact shoe in each pair being connected to the other terminal in said other pair of terminals and means for periodically and alternately closing one contact shoe in each pair and then the other contact shoe in each pair with their respective cylindrical conductors.

5 2. A device as called for in claim 1 wherein said last mentioned means includes solenoids, the movable members of which are operatively connected with said contact shoes.

10 3. A device as called for in claim 2 wherein said shoes are formed with a contact surface defining a segment of a cylinder corresponding to the outer cylindrical surface of the cylindrical conductors, said solenoids being adapted to shift said contact shoes to a position such that the contact surface of the shoes intimately engages the outer cylindrical surface of said cylindrical conductors.

15 4. A device as called for in claim 2 wherein said shoes are pivotally supported.

20 5. A device as called for in claim 2 wherein the operative connection between the movable elements of the solenoids and said shoes includes a resiliently yieldable member.

25 6. A device for periodically reversing the polarity of a D.C. current comprising a pair of input terminals adapted to be connected to a source of D.C. current, a pair of output terminals, a pair of conductors, each having a pair of broad, relatively large contact faces, one of said pair of terminals being electrically connected with said conductors, a first pair of contact members each movable to make with said two conductors, said contact members being connected with one of the terminals in the other pair of terminals, a second pair of contact members each movable to make with the two conductors, said contact members also having broad, relatively large contact faces movable into close face to face engagement with the contact faces of the conductors, said second pair of contact members being connected with the other terminal of said other pair of terminals, a plurality of four solenoids pivotally connected one with each contact member for operating the contact members and means for periodically and alternately energizing said solenoids in pairs for alternately moving each pair of said contact members to the make position.

30 7. An electro-mechanical current reversing unit comprising a support, a pair of electrically conducting tubular members on said support, a first pair of contact shoes pivotally mounted on said support and adapted to pivot into and out of contact one with each of said tubular members, a second pair of contact shoes pivotally mounted on said support and adapted to pivot into and out of engagement one with each of said tubular members, a pair of input terminals connected one with each of said tubular members, said input terminals being adapted to be connected to a source of direct current, a pair of output terminals, the contact members in one of said pairs being connected to one output terminal and the contact members in the other pair being connected to the other output terminal whereby the alternate closing of said two pairs of contacts reverses the polarity at said output terminals.

35 8. A current reversing unit as called for in claim 7 wherein said tubular members have a cylindrical outer surface and said shoes are formed with an arcuate contact surface defining a cylindrical segment, said contact surface of each shoe conforming to the outer cylindrical surface of said tubular members and being adapted for intimate engagement therewith throughout a substantially large area.

40 9. A current reversing unit as called for in claim 8 including solenoids for pivoting said shoes into and out of contact with said tubular members.

45 10. A current reversing unit as called for in claim 8 including a solenoid operatively connected with each shoe for pivoting the shoes into and out of contact with the tubular members.

50 11. A current reversing unit as called for in claim 10

including a resiliently yieldable connection between each solenoid and its shoe.

12. A current reversing unit comprising a frame structure, insulating support members on said frame structure, a pair electrically conducting tubular members of cylindrical shape mounted on said support members, two pair of contact shoes each insulatively supported on said frame structure for pivotal movement into and out of contact with the outer cylindrical surface of said tubular members, one shoe of each pair being adapted to contact one of the tubular members and the other shoe in each pair being adapted to contact the other tubular member, a pair of input terminals adapted to be connected to a source of direct current, said terminals being insulatively mounted on said frame structure, said input terminals being electrically connected one with each of said tubular members, a pair of output terminals insulatively mounted on said frame structure, one of said output terminals being electrically connected to each shoe of one pair and the other output terminal being electrically connected to each shoe of the other pair and means for alternately and periodically pivoting one shoe in each pair into contact with its respective tubular member and then the other shoe in each pair whereby the polarity at said output terminals is periodically reversed.

13. A current reversing unit as called for in claim 12 wherein said last mentioned means includes a solenoid for each contact shoe insulatively mounted on said frame structure, the movable element of each solenoid having

an insulated operative connection with its respective shoe.

14. A current reversing unit as called for in claim 13 wherein the contact shoes and their respective solenoids are disposed generally on diametrically opposite sides of the tubular members.

15. A current reversing unit as called for in claim 14 wherein said contact shoes are pivotally supported on said frame structure at one end thereof and the solenoids are operatively connected with the other ends of said contact shoes.

16. A current reversing unit as called for in claim 15 wherein said operative connection includes a link pivotally connected to the free end of each contact shoe and a spring connecting each link with the movable element of its respective solenoid.

17. A device as called for in claim 6 wherein said contact members are each pivotally supported at one end and have a linkage connection with said solenoids at their opposite ends, said linkage connection including a spring operative when the solenoid is energized to bias the contact member into contact with its respective conductor.
